UNITED STATES PATENT OFFICE.

JAMES HORTON, OF CHICAGO, ILLINOIS.

CRANE.

SPECIFICATION forming part of Letters Patent No. 508,476, dated November 14, 1893.

Application filed January 10, 1893. Serial No. 457,889. (No model.)

To all whom it may concern:

Be it known that I, JAMES HORTON, a citizen of the United States, residing at Chicago, county of Cook, State of Illinois, have invented 5 certain new and useful Improvements in Cranes, of which I do declare the following to be a full, clear, and exact description, reference being had to the accompanying drawings, forming part of this specification.

10 My present invention has relation more particularly to that class of cranes known as hydraulic cranes and in the accompanying drawings my invention is shown as embodying a hydraulic crane especially designed for the introduction into and withdrawal from re-heating furnaces of rails or other articles to be heated. I wish it understood however, that while I have illustrated what I regard as the preferred form of my invention, and its use 15 in connection with a class of work to which it is especially well adapted, the invention is not restricted to the details of construction shown since these may be varied by the skilled mechanic within wide limits, and features of 20 the invention may be employed for any purpose to which they are found adapted, without the adoption of my improvements as an 25 entirety.

Figure 1 is a view in side elevation of a hydraulic crane embodying my invention, the re-heating furnace in connection with which the apparatus is shown, being illustrated in vertical section. Fig. 2 is a plan view, parts being omitted. Fig. 3 is a view in longitudinal section through the hydraulic cylinder whereby the shifting of the load carriage is effected. Fig. 4 is a view in longitudinal section through the telescopic supply pipe whereby water or other fluid is delivered to the vertical cylinder that is sustained by the load carriage. Fig. 5 is a view in vertical section on line 5—5 of Figs. 1 and 2, the pendulum supply pipe being shown in elevation. Fig. 6 is a view of the telescopic pendulum supply pipe and its connections, parts being broken away for better illustration. Fig. 7 is a detail view of the load carriage and parts sustained thereby, certain parts being shown in horizontal section. Fig. 8 is a view in vertical section on line 8—8 of Fig. 7, parts being shown in elevation. Fig. 9 is an end view 50 of the main platform, the hydraulic cylinder

for shifting said platform being shown in vertical section. Fig. 10 is a view of the pipes whereby the water or other fluid is admitted to and discharged from the hydraulic cylinder whereby the rack bar of the load carriage is shifted. Fig. 11 is a detail front view of the gripping mechanism upon the load carrying arm. Fig. 12 is a detail sectional view on line 12—12, Fig. 11. Fig. 13 is a detail view in cross section taken at line 13—13, Fig. 12. Fig. 14 is a detail sectional view taken at line 14—14, Fig. 9. Fig. 15 is a detail side view of the parts shown in Fig. 14, the supporting bracket being shown in section. Fig. 16 is a detail sectional view of a four-way valve. Fig. 17 is a detail sectional view of a three-way valve.

A designates suitable uprights which serve by means of the brackets *a* to sustain the rails *a'* whereon the wheels of the main platform will travel. This main platform is preferably formed of the end trucks *B* and *B'* that are united together by the long rails or I-beams *B²* and *B³*. As these rails are of considerable length they will be braced by suitable bars 2 and 3 arranged at convenient points throughout their length. Each of the end trucks *B* and *B'* consists preferably of a single casting 80 having a vertical portion 5 and a horizontal portion 6, said horizontal portion having bifurcated ends 7 wherein are journaled the carrying wheels 8 of the platform.

Upon the rails or I-beams *B²*, *B³* of the main platform travel the wheels 10 of the load carriage *C*, the construction of which is more particularly shown in Figs. 1, 2, 7 and 8. This load carriage preferably comprises a body or horizontal portion 12 in the ends of which are 90 journaled the axles 13 of the wheels 10, and by preference the body 12 of the carriage has cast in one piece therewith a vertical cylinder *C'* through which passes the vertical lifting shaft *D*. This shaft *D* has attached thereto a piston *d* that works within the cylinder *C'* and the upper end *D'* of the shaft *D* has a groove *d'* therein to receive a rib 15 that is formed on the hub of the turning pinion *E* at the top of the vertical cylinder *C'*.

By reference more particularly to Fig. 8 of the drawings it will be seen that the cylinder *C'* is provided with a top plate *C²* bolted thereto, and in order to permit a free revolu-

- tion of the turning pinion E, the hub of this pinion is formed with an extension e that passes through the top plate C² of the cylinder, the lower end of this extension e being 5 screw threaded to receive a threaded ring 16 which serves to hold the pinion E in place upon the top plate C² of the cylinder C'. The hub of the pinion E is preferably provided with the stuffing box e' to prevent leakage.
- 10 The lower end of the cylinder C' is provided with a bushing 17 and with a stuffing box 18 conveniently bolted thereto as at 19 in order to guard against leakage at the lower end of the cylinder, and the casting at the lower end 15 of the cylinder C' is preferably formed with an open space 20 to permit the sections of the bushing 17 and of the stuffing box 18 to be placed in position. To the bottom of the casting wherein the cylinder C' is formed is 20 bolted an extension 21 having a bearing sleeve 22 through which passes the vertical shaft D. At the top and bottom respectively of the cylinder C' are connected the pipes 23 and 24 whereby water or other fluid will be 25 supplied to the cylinder in order to effect the shifting of the piston d and consequently the raising and lowering of the shaft D, as will presently be more fully described.

By reference more particularly to Figs. 1, 7 30 and 8 of the drawings it will be seen that with the turning pinion E engages the shifting rack bar F, the teeth of this rack bar being held in engagement with the pinion by means of the guide roller 25 that is journaled upon 35 a stud 26 rising from the top plate C² of the vertical cylinder C'. To the rack bar F is connected a piston rod F', the piston f of which rod travels within a horizontal cylinder F². One end of this cylinder F² is closed 40 by cap 26 that will be bolted to the head 27 that is threaded to engage the threaded end of the cylinder F², and the opposite end of the cylinder has a threaded portion that enters the threaded upper end 28 of a standard 45 29 (see Fig. 1), that is bolted to the horizontal portion 12 of the load carriage. To the upper end 28 of the standard 29 is bolted the head plate 30 of the cylinder through which passes the piston rod F', this head plate being 50 furnished with a suitable stuffing box 31 conveniently bolted thereto. The ends of the cylinder F² have attached thereto the pipes 32 and 33 for the passage of the water or other fluid whereby the shifting of the piston f 55 within the cylinder will be effected, as will presently more fully appear.

From the construction of parts thus far defined it will be seen that the main platform whereby the load carriage C is sustained can 60 be moved back and forth upon the rails a' while the load carriage C can be shifted upon the rails or I-beams B², B³ of the platform and at right angles to the line of travel of the platform. So also it is plain that by the admission of water under pressure to the cylinder C' the vertical shaft D (whereby the load to be shifted will be sustained) can be

raised and lowered, and by means of the rack bar F and the turning pinion E revolution can be imparted to the vertical shaft D in 7c order to swing the load carrying arm G at the end of the vertical shaft D in desired direction.

The mechanism whereby the shifting of the platform, of the load carriage and of the vertical load sustaining shaft D is effected will 75 next be described.

Suitably sustained above the apparatus is a main supply pipe H for water or other fluid and to the end of this pipe is united by suitable swivel coupling i the upper end of the telescopic supply pipe which consists of the sections I and I'. The section I is furnished at its lower end with a cap 38 and stuffing box 39 through which passes the section I', 85 and the lower end of the section I' is provided with a swivel coupling i' that is attached by the brackets 40 and 41 (see Figs. 1, 2 and 6) with one of the rails B² of the main platform. The construction of the swivel 90 coupling at the upper end of the telescopic pendulum supply pipe is the same as that illustrated at the lower end of such pipe, the brackets sustaining the swivel coupling i at the upper end being similar to the brackets 40 and 41. 95 It will thus be seen that as the main platform is moved back and forth the telescopic pendulum supply pipe will permit a continuous flow of water therethrough from the main supply pipe H (see dotted lines Fig. 5). To the 100 swivel coupling i' at the lower end of the pendulum supply pipe is connected, by means of bracket 40 (see Figs. 1, 2 and 6), a pipe 42, which is preferably curved as in Figs. 1 and 2 to pass outside the line of travel of the carriage C, and this pipe leads to a four-way coupling 43 which, as well as all of the supply pipes to be hereinafter described are supported by and moved with the main platform. From the coupling 43 water will pass by the 105 short pipe 44 into the four-way valve 45, to which are connected the pipes 46 and 47 that lead to the opposite ends of the platform shifting cylinder K. This cylinder K is mounted in manner free to slide upon the 110 long rod L to which is attached the piston l within the cylinder K. The ends of the cylinder K are furnished with the heads 50, 51, threaded to engage the threaded ends of the cylinder and to these heads are suitably 115 bolted the end plates 52 carrying the stuffing boxes 53, the end plates and stuffing boxes being perforated to receive the rod L. To the cylinder K are bolted the sectional bands 54 (see Figs. 9 and 14), the lower flanges 55 of 120 these bands serving to retain the blocks 56 that slide upon the rail 57. The rail 57 is formed of sections (see Fig. 15) the webs of which are cut away as shown at Fig. 15 to receive the brackets a that sustain the main 125 rails a' of the platform.

The cylinder K is connected to the end truck B of the main platform by bands 58 that encircle the cylinder and are bolted to

the truck B as at 59 so as to insure the movement of the platform with the cylinder, and preferably the axle 60 is extended from end to end of the platform to connect the wheels 5 in order to better insure the unison movement of both ends of the platform. The four-way valve 45 is provided with a handle 60^a that extends downward in position to be manipulated by the operator standing upon the suspended frame 61 that is supported by suitable rods connected to the main platform, and it will be seen that when the handle 60^a is shifted so as to cause water to flow from the four-way valve chamber 45 through the pipe 46 and into the corresponding end of the cylinder K, the cylinder will be shifted in the direction of the arrow, Fig. 9 and will cause a like movement of the main platform in such direction. While the cylinder and platform are thus shifted, a free escape of the water from the opposite end of the cylinder K will flow through the pipe 47 and through one of the channels of the four-way valve 45, whence it will pass by suitable discharge pipe into a gutter conveniently arranged beneath the path of travel of the platform. It is obvious also that if the handle 60^a of the four-way valve 45 is reversed so as to cause the passage of water through the pipe 47 and into the cylinder K, the direction of travel of the cylinder K and of the platform will be reversed, and the water from the opposite end of the cylinder K will escape by way of the pipe 46.

35 In order to enable the carriage C to be shifted back and forth upon the rails of the main platform I have provided a hydraulic cylinder M that is attached to the main platform in suitable manner, this cylinder M having screw threaded heads m and m', the head m' having bolted thereto a cap plate m² and the stuffing box m³ through which passes the piston rod N. One end of this piston rod N has a piston n working within the cylinder M, while the opposite end of this piston rod is connected to an arm 68 that is bolted to the load carriage C (see Fig. 2). To one end of the cylinder M connects a water pipe 70 and to the opposite end of this cylinder connects a water pipe 71. Both of these pipes lead to a four-way valve 72 located at one end of the platform above the operator's stand 61, this four-way valve 72 being furnished with a handle 73 whereby a supply and discharge of water through the pipes 70 and 71 can be controlled. Hence it will be seen that when the operator desires to move the carriage C in one direction, for example toward the operator's stand 61 he will shift the handle 73 of the valve 72 so as to cause the supply of water (which is delivered to the four-way valve 72 by a pipe 74 from the main coupling 43) to pass through the pipe 70 into the cylinder M. The water thus entering the cylinder will force the piston n outward causing the carriage C to move toward the operator's stand, and the water from the opposite side

of the piston will escape by way of the pipe 71 into the four-way valve 72, whence it will pass by suitable discharge pipe into the gutter arranged to receive the waste water. It is obvious that when it is desired to reverse the direction of the carriage C it will only be necessary for the operator to reverse the valve lever 73, thereby causing the admission of 75 water to the cylinder M through the pipe 71 and the discharge of water from such cylinder through the pipe 70.

In order to raise and lower the vertical load sustaining shaft D (see Fig. 8) I connect the 80 pipe 24 at the lower end of the cylinder C' with the telescopic supply pipe formed of the sections O and O' (see Fig. 4), the section O of this pipe having one end closed by cap o and having its opposite end provided with a 85 head o' and a stuffing box o² through which passes the section O'. This section O' of the supply pipe leads to the end of the platform and is there fixed as shown at 80 in Fig. 2 and by means of the cross pipe 81 it is connected 90 with a three-way valve 82 that receives a supply of water from the main coupling 43, this valve 82 being furnished with a suitable discharge pipe that empties into the gutter for waste water and being furnished also with 95 a hand lever 83. The pipe 23 at the upper end of the cylinder C' is simply a vent pipe to permit the admission and the escape of air above the piston d, since it is not necessary to employ power for moving downward the piston d, as the weight of the load and of the vertical shaft D will effect the downward movement of the shaft.

From the foregoing description it will be seen that when the operator shifts the valve 105 lever 83 so as to cause water to pass through the pipes 81, O', O and 24, into the cylinder C', the piston d will be forced upward in the cylinder and will carry with it the load sustaining shaft D. When the operator reverses 110 the lever 83 the weight of the shaft D and its load will draw downward the piston d forcing the water to escape through the pipes by which it was delivered to the cylinder.

To enable the load sustaining shaft D to be 115 turned in order to permit the load carrying arm G to be swung in desired direction, through the medium of the turning pinion E shifting rack F, cylinder F² and piston f, as hereinbefore defined, I connect one end of 120 the cylinder F² by means of a pipe 32 to a shifting supply and discharge pipe 90 and I connect the opposite end of this cylinder F² by a pipe 33 to a similar shifting supply and discharge pipe 91, the construction of which 125 pipes is more particularly illustrated in Figs. 7 and 10 of the drawings. The shifting supply pipe 90 is furnished at its opposite ends with the heads 92 to which are bolted the caps 93 and stuffing boxes 94 and through these 130 caps and stuffing boxes passes the pipe 95 that connects by a bent pipe 96 with a four-way valve 97 that will be furnished with a valve lever 98 and with a suitable waste pipe

leading to the common gutter for waste water. In like manner the pipe 91 will be provided with heads 92, cap plates 93 and stuffing boxes 94, through which cap plates and stuffing boxes extends the fixed pipe 99 that connects by a cross pipe 100 with the four-way valve 97. It will be observed that each of the pipes 95 and 99, are fixed pipes a constant communication being maintained between the shifting pipes 90 and 91 and the fixed pipes 95 and 99 by means of the orifices 101. Hence it will be seen that when water is to be admitted into the cylinder F² for the purpose of shifting the rack bar F in order to turn the vertical shaft D, it is only necessary for the operator to move in proper direction the valve lever 98 of the four-way valve 97. When water is admitted by the fixed pipe 95 and shifting pipe 90, and pipe 33 to the cylinder F², the piston f will be forced backward from the position shown in Fig. 7, and at the same time water will escape from the opposite side of the piston through the pipe 32, the shifting pipe 91, the fixed pipe 99, and the pipe 100 into the valve 97 whence it will pass by a waste pipe into the gutter for waste water. By reversing the hand lever 98, it is obvious that a reverse movement of the piston f and of the rack bar F can be effected. Hence it will be seen that by the manipulation of the proper levers, the operator upon his stand 61 can cause the movement of the main platform and of the load carriage and can also effect the vertical lifting and the turning of the load sustaining shaft D in order to raise and turn to the desired position the load carrying arm G.

When my apparatus is to be employed for the introduction and withdrawal of blooms or like articles into and from re-heating furnaces I prefer to construct the load carrying arm G and its gripping mechanism as more particularly illustrated in Figs. 1, 11, 12 and 13 of the drawings. This arm G has its hub g connected to the lower end of the vertical shaft D and the under side of this arm G is formed with a groove or channel for the operating rod P that extends from end to end of the arm and serves to control the movement of the gripper jaws R and R' at the free end of the arm G. One of the R jaws is bifurcated at its upper end to receive the upper end of the gripper jaw R' and through the upper ends of these jaws passes the stud r whereon the jaws R and R' are pivoted, this stud being held within a socket in the end of the load carrying arm G and being provided with a head r' to retain the pivoted jaws in place. The bifurcated jaw R is formed with the slots r² to receive the eccentrics or cams p² of the operating rod P, and in like manner the jaw R' is formed with a slot r³ to receive the eccentric or cam p³ of the rod P. The outer end of the operating rod P is sustained by a journal plate p⁴ bolted to the under side of the arm G, while the opposite end of this rod P is journaled in a hanger p⁵ that

is bolted to the hub g of the arm G and is furnished with a handle p⁶ whereby the rod can be turned as desired. The free ends of the gripper jaws R and R' are preferably furnished with pins r⁸ to enable the jaws to more firmly grip the bloom or bar to be shifted.

From the above description it will be seen that when it is desired to lift a bloom or bar W (see Fig. 1), the furnace attendant will turn the handle p⁶ so as to cause the cams or eccentrics p², p³ at the opposite end of the rod P to turn the jaws R, R' in such manner as to force their free ends to firmly engage the bar or bloom W. The operator upon the stand 61 will then, by the mechanism hereinbefore described, cause a backward movement of the carriage C so as to withdraw the bar or bloom W from the re-heating furnace X and will afterward shift the platform and turn the load carrying arm G in order to deposit the bar or bloom W at the desired point. In order to protect the operating rod from being struck by the bar or rail W, I provide the under side of the load carrying arm G with a shield or plate T conveniently bolted thereto.

It is obvious that the precise construction of the gripper jaws and of the load carrying arm may be varied to suit the character of the work for which they are to be employed.

Having thus described my invention, what I claim as new, and desire to secure by Letters Patent, is—

1. The combination with suitable rails of a movable platform mounted upon said rails, a cylinder connected and movable with said platform for shifting the same, and a fixed piston rod extending through both ends of said cylinder, and suitable pipes for delivering fluid to said cylinder upon opposite sides of the piston, whereby the platform can be shifted back and forth, substantially as described.

2. The combination with suitable rails of a movable platform, a hydraulic cylinder connected to said platform and movable therewith, a fixed piston rod extending through said cylinder, and a supplemental rail for sustaining said cylinder, substantially as described.

3. The combination with a suitable platform of a load carriage movably sustained thereon, a double acting hydraulic cylinder carried by said platform and arranged out of the line of travel of the load carriage, a piston rod for said cylinder, an arm connecting the free end of the piston rod to the load carriage, and suitable delivery and discharge pipes for said cylinder, substantially as described.

4. The combination of a movable platform, a load carriage mounted upon and movable on said platform, a hydraulic cylinder connected to and movable with said platform, a fixed piston rod extending through both ends of said cylinder, suitable pipes for delivering

fluid to both ends of said cylinder, a hydraulic cylinder carried by said platform and extending in the direction of its length and a piston rod for said cylinder connected with the load carriage, said piston rod and cylinder being of sufficient length to effect the back and forth movement of said load carriage, substantially as described.

5 5. The combination with a suitable load carriage of a hydraulic cylinder sustained thereby, a vertically movable and rotatable shaft extending through said cylinder and a load carrying arm connected to and sustained by said shaft, whereby said arm can be bodily lifted and rotated, substantially as described.

10 6. The combination with a platform of a load carriage movably mounted upon said platform, a vertical cylinder sustained by said load carriage, a rotatable and vertically movable lifting shaft extending through both ends of said cylinder, a pinion mounted upon the upper end or extension of said lifting shaft, and suitable means for turning said pinion, substantially as described.

15 7. The combination with a platform of a load carriage movably mounted upon said platform, a vertical cylinder sustained by said

load carriage, a vertically movable and rotatable lifting shaft passing through both ends of said cylinder, a pinion connected to 30 said lifting shaft, a rack bar for engaging said pinion, and a cylinder and piston rod mounted upon and movable with said load carriage for operating said rack bar, substantially as described.

35 8. The combination with a platform of a load carriage movably mounted thereon, a vertical cylinder sustained by said carriage, a rotatable shaft extending through said cylinder, a rack bar and pinion for rotating said 40 shaft, a cylinder and piston movable with said load carriage for operating the rack bar and pinion and movable supply and discharge pipes carried by said load carriage and fixed pipes extending through said movable supply and discharge pipes whereby fluid is delivered to the cylinder in order to operate the rack bar and pinion, substantially as described.

45 JAMES HORTON.
